UNITED STATES PATENT OFFICE.

F. ROBERT SEIDENSTICKER, OF MERIDEN, CONNECTICUT, ASSIGNOR TO THE
BRADLEY & HUBBARD MANUFACTURING COMPANY, OF SAME PLACE.

DESIGN FOR A LAMP-BRACKET.

SPECIFICATION forming part of Design No. 12,301, dated June 7, 1881.

Application filed April 30, 1881. Term of patent 7 years.

To all whom it may concern:

Be it known that I, F. ROBERT SEIDENSTICKER, of Meriden, in the county of New Haven and State of Connecticut, have invented 5
a new Design for Lamp-Brackets; and I do hereby declare the following, when taken in connection with the accompanying drawing and the letters of reference marked thereon, to be a full, clear, and exact description of the 10 same, and which said drawing constitutes part of this specification and represents a side view.

This invention relates to a design for a bracket-arm for lamps, for wall-brackets, or 15 as an arm for chandeliers; and it consists in the construction and ornamentation, as shown in the accompanying illustration.

At the point of connection with the socket or chandelier the bracket-arm starts from a 20 square boss, *a*, running upward, turns at a right angle for a short distance, then a gradual curve downward to the key, thence continuing substantially the same curve upward, terminating at the lamp-seat. The face of the 25 arm is sunk or slightly recessed, the edges forming a band which terminates in scroll-work at the lamp-seat. At the horizontal or right-angular part of the arm an ornamental extension, *A*, runs upward to the seat *b* for 30 the shade-arm. From the forward part of this extension an ornament of scroll-work extends downward upon the curved portion of the bracket-arm. From an extension downward from the boss *a* a scroll-work spring and extends to the under side of the bracket-arm, to 35 give the appearance of support to the arm.

The basket for the support of the lamp-fount rests upon the seat on the bracket. Its lower section or base in outline shows a succession of cavetto with intermediate fillets. The first 40 section, *c*, of the basket presents a convex shape, and the upper section, *d*, the reverse, with a section, *e*, between, showing an offset between it and the sections *c d*. The section *e* shows a series of openings or panels, *f*. The 45 upper edge of the upper section, *d*, is furnished with a series of semicircular scallops with intermediate semicircular recesses, with a horizontal shoulder between the scallops and the recesses, the section *e* ornamented by a series 50 of points or scallops.

I claim—

1. The design for lamp-bracket arm, consisting of the boss *a*, from which the arm springs upward, thence turning at right angles, thence 55 downward in a curved shape, terminating in scroll-work at the lamp-seat, with the ornamental extension *A* from the horizontal part of the arm, and scroll-work from the said extension down upon the arm, and similar scroll-work upon the under side of the arm, as shown in the accompanying illustration.

2. The design for lamp-bracket-arm fount-support, consisting of the convex section *c*, concave section *d*, with the intermediate offset section, *e*, said sections ornamented as described, and shown in the accompanying illustration. 65
